UNITED STATES PATENT OFFICE.

ALFRED JOHN RAYNOR, OF TORONTO, CANADA.

WATER-TUBE BOILER.

No. 822,932.

Specification of Letters Patent.

Patented June 12, 1906.

Application filed May 11, 1903. Serial No. 156,601.

To all whom it may concern:

Be it known that I, ALFRED JOHN RAYNOR, a subject of the King of England, and a resident of the city of Toronto, Province of Ontario, Canada, have invented certain new and useful Improvements in Water-Tube Boilers, of which the following is a specification.

The object of my invention is to provide a boiler of the water-tube type of an extremely simple and cheap form of construction, having great heating-surface, which may be easily separated into its component parts for cleaning or renewal purposes.

To such ends my invention consists, in substance, of a plurality of superposed water-tube sections, each consisting of two horizontal end pipes arranged in parallel and in communication with one another by curved or S-shaped cross-pipes, a coupling for each end 15 of the end pipes forming a perpendicular water-passage, which couplings when superposed form riser pipes or passages, a like plurality of superposed water-tube sections arranged alternately with the first section 20 of like end pipes arranged one inside and the other outside of the end pipes of the first-mentioned section and connected together by like curved or S-shaped cross-pipes each of which end pipes is provided with 25 similar end couplings, which when superposed and secured together form riser pipes or passages similar to the like riser pipes or passages of the inner section, pipes forming a communication between the riser pipes or 30 passages of one section and with the like pipe or passage of the other section immediately adjacent thereto at the top and bottom, a steam drum or dome in communication with the riser pipes or passages at one end and 35 with the other riser pipes or passages at the other end, a fire-box the sides and bridge-wall of which form a water-chamber in communication at one end with the riser pipes on one side at the bottom and also in communication in like manner with the riser-pipes on the other side, a return-pipe in communication with the steam drum or dome and with the riser-pipes on one side at the bottom, a like return-pipe in communication with the 40 steam drum or dome and with the bottom portion of the riser-pipes at the other end, a casing inclosing the boiler-battery formed by the superposed sections of S-shaped pipes and riser-couplings having removable walls, 45 and a smoke-flue in communication with the casing-chamber, although it is not to be un-

derstood that my invention is limited to a device necessarily comprising at once all of the devices and parts or the exact arrangement of devices and parts set forth, as the same 60 consists in the construction of certain devices and parts and the particular combination and arrangement of certain devices and parts, all as hereinafter more fully set forth in the specification and pointed out in claims. 65

My said invention is fully shown and described in the following specification, of which the accompanying drawings form a part, wherein similar letters or numerals of reference designate like or equivalent parts 70 wherever found throughout the several views, and in which—

Figure 1 is a side view of my improved boiler or steam-generator in central vertical section. Fig. 2 is a front view thereof, looking in the direction of the arrow shown in Fig. 1 in section on the line *b b* of such figure. Fig. 3 is a top view thereof in section on the line *cc* of Fig. 1; and Fig. 4 is a front elevation of the boiler-battery, showing in dotted outline the direction of removing one of the pipe-sections.

Referring to the drawings, the reference-letter A designates the battery of the boiler; B, the casing-chamber; C, the water-walled 85 fire-box; D, the steam drum or dome; E, the smoke-flue for the escape of the products of combustion from the fuel consumed in the fire-box, and F the brick or other outer casing in which the entire apparatus is usually in- 90 closed upon the sides and by which it is supported in the manner usual in such devices.

The battery A consists of a plurality of horizontal superposed pipe-sections, each consisting of two end pipes 11, arranged in 95 parallel and connected together by a plurality of curved or S-shaped cross-pipes 12 of any desired number—usually four, as shown in Fig. 3—such cross-pipes being secured to the end pipes by suitable connections, usually of the flanged and bolted form shown at 13. The end pipes are each provided at either end with suitable T-couplings 14, also usually of the flange-and-bolt form shown, which couplings when the various sections 100 are secured together in the superposed position form continuous riser pipes or passages G at each of the four corners of the battery. Outside of and parallel with the pipes 11 are arranged similar end pipes 15, of similar 105 form and construction, in line with the interstices or spaces between such pipes 12, from

one to the other of which extend cross-pipes 16, of similar form and secured in like manner to such end pipes 15 as are the cross-pipes 12 to the end pipes 11, and such end pipes 15 are provided at either end with **T**-couplings 17, similar in form to the couplings 14, which when in superposed position with the cross-pipes 16 alternating with the cross-pipes 12 form riser pipes or passages H, similar to the like riser pipes or passages formed by the **T**-couplings 14. The risers G on either side are connected with the adjacent riser H at the top by a circulating-pipe 20 and at the bottom by a like circulating-pipe 21 on one side, and on the other side they enter the water-walled fire-box C, the arrangement being such that the prismatic pipe-piles formed at either end of the battery by each set of adjacent riser G and H and end pipes 11 and 15 will be of the rhomboidal form shown for the purpose of facilitating the removal of the various sections, as hereinafter set forth. The fire-box C is formed of boiler metal or other suitable material in such manner that the same is provided on either side with a hollow side-wall water-chamber 22, which chambers are in communication with one another at the rear of the fire-box by a like hollow water-chambered bridge-wall 23, and such side wall water-chambers 22 are in communication one with one and one with the other of the rhomboidal prismatic pipe-piles adjacent to the bottom thereof by way of suitable pipes 24 and 25, and such piles are also in communication at the bottom one with a feed-pipe 26 and the other with a blow-off pipe 27. The fire-box when used for solid fuel is also provided with suitable grate-bars 28 of any desired form. The boiler-battery so formed is supported by and inclosed in a radiation-casing 29, forming a hot-air chamber M, the walls and top plates of said radiation-chamber being secured together by suitable corner-plates 29', secured at the edges by bolts, so that the same may be removed bodily for the purpose of gaining access to the battery of pipes and tubes, the risers G and H alone extending upward through the top plate of such radiation-chamber and one set thereof being in communication with the steam drum or dome D at one end thereof by way of a pipe 30 and the other set being in communication with such drum by way of a similar pipe 31. The steam drum or dome is also usually provided with a return-water pipe 32, located at the center, as shown in Fig. 1, from which a circulating return-pipe 33 leads to the bottom of the rear rhomboidal prismatic pipe-pile, and a like circulating return-pipe 34 leads to the bottom of the front similar pipe-pile.

The battery is of course provided with the usual accessories—such as water-gages, pressure-gages, gage-cocks, &c.; but these forming no part of my invention I have not deemed

it necessary to show more than the water-gage glass, which is usually in communication by way of suitable pipes 35 and 36 with the steam drum or dome D and with the front pipe 31, which forms a communication between that end of the drum and the top of the adjacent rhomboidal pipe-pile.

In communication with the radiation-chamber at the top at convenient points, usually adjacent to the prismatic pipe-piles, is a lead-flue 37, in communication with a main smoke-flue E, leading to a suitable smoke-stack. (Not shown.)

By this construction it will be seen that should any portion of any of the superposed sections forming the sections of the battery blow out or become sealed by simply removing one wall of the radiating-chamber and taking out the bolts securing the four couplings forming the risers at the four corners thereof such section may be removed bodily, repaired or cleaned, and reinserted without the slightest disturbance of the other sections, such removal being either to the front or rear, according to the position of the section, it being always removed outward from the risers to which it is connected, as fully shown in dotted lines in Fig. 4 of the drawings.

Having thus described my invention, what I claim as new, and desire to secure by Letters Patent of the United States, is—

1. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, substantially as and for the purposes set forth.

2. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, substantially as set forth.

3. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, substantially as set forth.

4. In a water-tube boiler, the combination with a battery composed of horizontal tubes connected together by way of riser-tubes, of a fire-box water-chamber formed in the bridge, end and side walls of the fire-box in free communication with each other, and in communication with the riser pipes or tubes.

5. A water-tube boiler comprising a battery composed of a plurality of riser-pipes each formed of a plurality of **T**-couplings

superposed one upon the other, the couplings in the same plane being connected in pairs to one another by end pipes which end pipes are connected together by cross-pipes, a second 5 battery-section of similar construction the component sections of which formed of the riser-couplings end and cross pipes have their cross-pipes alternately arranged between the cross-pipes of the first-named sections, and 10 pipes connecting the adjacent risers of the two sections together at the top and bottom, substantially as set forth.

6. A water-tube boiler comprising a battery composed of a plurality of riser-pipes 15 each formed of a plurality of **T**-couplings superposed one upon the other, the couplings in the same plane being connected in pairs to one another by end pipes which end pipes are connected together by curved cross-pipes, a 20 second battery-section of similar construction the component sections of which formed of the riser-couplings end and cross pipes have their cross-pipes alternately arranged between the cross-pipes of the first-named 25 section, and pipes connecting the adjacent risers of the two sections together at the top and bottom, substantially as set forth.

7. A water-tube boiler comprising a battery composed of a plurality of riser-pipes 30 each formed of a plurality of **T**-couplings superposed one upon the other, the couplings in the same plane being connected in pairs to one another by end pipes which end pipes are connected together by **S**-shaped cross-pipes, 35 a second battery-section of similar construction the component sections of which formed of the riser-couplings end and cross pipes have their cross-pipes alternately arranged between the cross-pipes of the first-named 40 section, and pipes connecting the adjacent risers of the two sections together at the top and bottom, substantially as set forth.

8. A water-tube boiler comprising a battery composed of a plurality of riser-pipes 45 each formed of a plurality of **T**-couplings superposed one upon the other, the couplings in the same plane being connected in pairs to one another by end pipes which end pipes are connected together by cross-pipes, a second 50 battery-section of similar construction to the first section the component sections of which formed of the riser-couplings end and cross pipes have their cross-pipes alternately arranged between the cross-pipes of the first-named 55 sections, and pipes connecting the adjacent risers of the two sections together at the top and bottom, and a steam drum or dome in communication with the riser at the top, substantially as set forth.

9. A water-tube boiler comprising a battery composed of a plurality of riser-pipes each formed of a plurality of **T**-couplings superposed one upon the other, the couplings in the same plane being connected in pairs to 60 one another by end pipes which end pipes are

connected together by curved cross-pipes, a second battery-section of similar construction the component sections of which formed of the riser-couplings end and cross pipes have their cross-pipes alternately arranged 70 between the cross-pipes of the first-named section, and pipes connecting the adjacent risers of the two sections together at the top and bottom, and a steam drum or dome in communication with the risers at the top, 75 substantially as set forth.

10. A water-tube boiler comprising a battery composed of a plurality of riser-pipes each formed of a plurality of **T**-couplings superposed one upon the other, the couplings 80 in the same plane being connected in pairs to one another by end pipes which end pipes are connected together by **S**-shaped cross-pipes, a second battery-section of similar construction to the first section the component sections of which formed of the riser-couplings 85 end and cross pipes have their cross-pipes alternately arranged between the cross-pipes of the first-named section, pipes connecting the adjacent risers of the two sections to- 90 together at the top and bottom, and a steam drum or dome in communication with the risers at the top, substantially as set forth.

11. A water-tube boiler comprising a battery composed of a plurality of riser-pipes 95 each formed of a plurality of **T**-couplings superposed one upon the other, the couplings in the same plane being connected in pairs to one another by end pipes which end pipes are connected together by cross-pipes, a second 100 battery-section of similar construction the component sections of which formed of the riser-couplings end and cross pipes have their cross-pipes alternately arranged between the cross-pipes of the first-named section, pipes 105 connecting the adjacent risers of the two sections together at the top and bottom, and a fire-box having the side and bridge walls in the form of a water-chamber in communication with the battery, substantially as set 110 forth.

12. A water-tube boiler comprising a battery composed of a plurality of riser-pipes each formed of a plurality of **T**-couplings superposed one upon the other, the couplings in 115 the same plane being connected in pairs to one another by end pipes which end pipes are connected together by curved pipes, a second battery-section of similar construction the component sections of which formed of the 120 riser-couplings end and cross pipes have their cross-pipes alternately arranged between the cross-pipes of the first-named section, pipes connecting the adjacent risers of the two sections together at the top and bottom, and a 125 fire-box having the side and bridge walls in the form of a water-chamber in communication with the battery, substantially as set forth.

13. A water-tube boiler comprising a bat- 130

tery composed of a plurality of riser-pipes each formed of a plurality of **T**-couplings superposed one upon the other, the couplings in the same plane being connected in pairs to 5 one another by end pipes which end pipes are connected together by **S**-shaped cross-pipes, a second battery-section of similar construction the component sections of which formed of the riser-couplings end and cross pipes 10 have their cross-pipes alternately arranged between the cross-pipes of the first-named section, pipes connecting the adjacent risers of the two sections together at the top and bottom, and a fire-box having the side and 15 bridge walls in the form of a water-chamber in communication with the battery, substantially as set forth.

14. A water-tube boiler comprising a battery composed of a plurality of riser-pipes 20 each formed of a plurality of **T**-couplings superposed one upon the other, the couplings in the same plane being connected in pairs to one another by end pipes which end pipes are connected together by cross-pipes, a second 25 battery-section of similar construction the component sections of which formed of the riser-couplings end and cross pipes have their cross-pipes alternately arranged between the cross-pipes of the first-named section, pipes connecting the adjacent risers of 30 the two sections together at the top and bottom, a steam drum or dome in communication with the risers at the top, and a fire-box having the side and bridge walls in the form 35 of a water-chamber in communication with the battery, substantially as and for the purposes set forth.

15. A water-tube boiler comprising a battery composed of a plurality of riser-pipes 40 each formed of a plurality of **T**-couplings superposed one upon the other, the couplings in the same plane being connected in pairs to one another by end pipes which end pipes are connected together by curved cross-pipes, a 45 second battery-section of similar construction the component sections of which formed of the riser-couplings end and cross pipes have their cross-pipes alternately arranged between the cross-pipes of the first-named section, pipes connecting the adjacent risers of 50 the two sections together at the top and bottom, a steam drum or dome in communication with the risers at the top, and a fire-box having the side and bridge walls in the 55 form of a water-chamber in communication with the battery, substantially as set forth.

16. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, a second battery-section of similar construction 60 the component sections of which formed of the riser-couplings end and cross pipes have their cross-pipes alternately arranged between the cross-pipes of the first-named section, and pipes connecting the adjacent risers of the two sections together at the top and bottom, the pipe-piles at the end of the battery formed by the risers end pipes and connecting top and bottom pipes being each 65

of the riser-couplings end and cross pipes have their cross-pipes alternately arranged between the cross-pipes of the first-named section, pipes connecting the adjacent risers of the two sections together at the top and 70 bottom, a steam drum or dome in communication with the risers at the top, and a fire-box having the side and bridge walls in the form of a water-chamber in communication with the battery, substantially as set forth. 75

17. A water-tube boiler comprising a battery composed of a plurality of riser-pipes each formed of a plurality of **T**-couplings superposed one upon the other, the couplings in the same plane being connected in pairs to 80 one another by end pipes which end pipes are connected together by cross-pipes, a second battery-section of similar construction the component sections of which formed of the riser-couplings end and cross pipes have their 85 cross-pipes alternately arranged between the cross-pipes of the first-named section, and pipes connecting the adjacent risers of the two sections together at the top and bottom, the pipe-piles at the ends of the battery 90 formed by the risers, end pipes and connecting the top and bottom pipes being each in the form of a rhomboidal prism, substantially as set forth.

18. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second battery-section of similar construction the component sections of which formed of the riser-couplings end and cross-pipes have their cross-pipes alternately arranged 105 between the cross-pipes of the first-named section, and pipes connecting the adjacent risers of the two sections together at the top and bottom, the pipe-pile at the end of the battery formed by the risers end pipes and connecting top and bottom pipes being each 110 in the form of a rhomboidal prism, substantially as set forth.

19. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, a second battery-section of similar construction the component sections of which formed of the riser-couplings end and cross pipes have their cross-pipes alternately arranged between the cross-pipes of the first-named 115 section, and pipes connecting the adjacent risers of the two sections together at the top and bottom, the pipe-piles at the end of the battery formed by the risers, end pipes and connecting top and bottom pipes being each 120

130

in the form of a rhomboidal prism, substantially as set forth.

20. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a return circulating pipe or pipes forming a communication between the top and bottom portions of the boiler, substantially as set forth.

21. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a return circulating pipe or pipes forming a communication between the top and bottom portions of the boiler, substantially as set forth.

22. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a return circulating pipe or pipes forming a communication between the top and bottom portions of the boiler, substantially as and for the purposes set forth.

23. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second battery-section of similar construction the component sections of which formed of

riser-couplings end and cross pipes have their cross-pipes alternately arranged between the cross-pipes of the first-named section, pipes connecting the adjacent risers of the two sections together at the top and bottom, a steam drum or dome in communication with the riser at the top, and a return circulating pipe or pipes forming a communication between the top and bottom portions of the boiler, substantially as set forth.

24. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a steam drum or dome in communication with the risers at the top, and a return circulating pipe or pipes forming a communication between the top and bottom portions of the boiler.

25. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second battery-section of similar construction the component sections of which formed of the riser-couplings end and cross pipes of the first-named section, pipes connecting the adjacent risers of the two sections together at the top and bottom, a fire-box having the side and bridge walls in the form of a water-chamber in communication with the battery, and a return circulating pipe or pipes forming a communication between the top and bottom portions of the boiler.

26. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a fire-box having the side and bridge walls in the form of a water-chamber in communication with the battery, and a return circulating pipe or pipes forming a commun

cation between the top and bottom portions of the boiler.

27. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, 10 a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a fire-box having the side and bridge walls in the form of a water-chamber in communication with the battery, and a 15 return circulating pipe or pipes forming a communication between the top and bottom portions of the boiler.

28. A water-tube boiler comprising a battery composed of a plurality of riser-pipes 25 each formed of a plurality of **T**-couplings superposed one upon the other, the couplings in the same plane being connected in pairs to one another by end pipes which end pipes are connected together by cross-pipes, a second 30 battery-section of similar construction the component sections of which formed of the riser-couplings end and cross pipes have their cross-pipes alternately arranged between the cross-pipes of the first-named sections, and pipes connecting the adjacent risers of the 35 two sections together at the top and bottom, the riser-couplings of one set of sections being staggered to the riser-couplings of the other set of sections.

40 29. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second 45 battery-section of similar construction the component sections of which formed of the riser-couplings end and cross pipes have their cross-pipes alternately arranged between the cross-pipes of the first-named section, and pipes connecting the adjacent risers of the two sections together at top and bottom, the riser-couplings of one set of sections 50 being staggered to the riser-couplings of the other set of sections.

55 30. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, a second 60 battery-section of similar construction the component sections of which formed

of the riser-couplings end and cross pipes have their cross-pipes alternately arranged between the cross-pipes of the first-named sections, and pipes connecting the adjacent risers of the two sections together at the top and bottom, the riser-couplings of one set of sections being staggered to the riser-coupling of the other set of sections. 70

31. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second 80 battery-section of similar construction to the first section the component sections of which formed of the riser-couplings end and cross pipes have their cross-pipes alternately arranged between the cross-pipes of the first-named section, and pipes connecting the adjacent risers of the two sections together at the top and bottom, and a steam drum or dome in communication with the riser at the top, the riser-couplings of one set of sections 85 being staggered to the riser-couplings of the other set of sections. 90

32. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second 95 battery-section of similar construction the component sections of which formed of the riser-couplings end and cross pipes have their cross-pipes alternately arranged between the cross-pipes of the first-named section, and pipes connecting the adjacent risers of the two sections together at the top and bottom, and a steam drum or dome in communication with the risers at the top, the riser-couplings of one set of sections 100 being staggered to the riser-couplings of the other set of sections. 105

33. A water-tube boiler comprising a battery composed of a plurality of riser-pipes each formed of a plurality of **T**-couplings superposed one upon the other, the couplings in the same plane being connected in pairs to 115 one another by end pipes which end pipes are connected together by **S**-shaped cross-pipes, a second-battery section of similar construction to the first section the component sections of which formed of the riser-couplings 120 end and cross pipes have their cross-pipes alternately arranged between the cross-pipes of the first-named section, pipes connecting the adjacent risers of the two sections together at the top and bottom, and a steam drum or 125 dome in communication with the risers at the top, the riser-couplings of one set of sections being staggered to the riser-couplings of the other set of sections.

34. A water-tube boiler comprising a bat- 130

5 tery composed of a plurality of riser-pipes each formed of a plurality of **T**-couplings superposed one upon the other, the couplings in the same plane being connected in pairs to one another by end pipes which end pipes are connected together by cross-pipes, a second 10 battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a fire-box having the side and bridge walls in the form of a water-chamber 15 in communication with the battery, the riser-couplings of one set of sections being staggered to the riser-couplings of the other sections.

20 35. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved pipes, a second 25 battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a fire-box having the side and bridge 30 walls in the form of a water-chamber in communication with the battery, the riser-couplings of one set of sections being staggered to the riser-couplings of the other set of sections.

35 36. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, a second 40 battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a fire-box having the side and bridge walls in the form of a water-chamber in communication with the battery, the riser-couplings of one set of sections being staggered to the riser-couplings of the other set of sections.

45 37. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second 50 battery of similar construction the compo-

50 nent sections of which formed of the riser-couplings end and cross pipes have their cross-pipes alternately arranged between the cross-pipes of the first-named section, pipes connecting the adjacent risers of the two sections together at the top and bottom, a steam drum or dome in communication with the risers at the top, and a fire-box having the side and bridge walls in the form of a water-chamber in communication with the battery, 75 the riser-couplings of one set of sections being staggered to the riser-couplings of the other set of sections.

38. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, 80 a second battery-section of similar construction the component sections of which formed of the riser-couplings end and cross pipes have their cross-pipes alternately arranged between the cross-pipes of the first-named 85 section, pipes connecting the adjacent risers of the two sections together at the top and bottom, a steam drum or dome in communication with the risers at the top, and a fire-box having the side and bridge walls in the 90 form of a water-chamber in communication with the battery, the riser-couplings of one set of sections being staggered to the riser-couplings of the other set of sections.

39. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, 100 a second battery-section of similar construction the component sections of which formed of the riser-couplings end and cross pipes have their cross-pipes alternately arranged 105 between the cross-pipes of the first-named section, pipes connecting the adjacent risers of the two sections together at the top and bottom, a steam drum or dome in communication with the risers at the top, and a fire-box having the side and bridge walls in the 110 form of a water-chamber in communication with the battery, the riser-couplings of one set of sections being staggered to the riser-couplings of the other set of sections.

40. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second 115 battery-section of similar construction the component sections of which formed of the riser-couplings end and cross pipes have 120

their cross-pipes alternately arranged between the cross-pipes of the first-named section, and pipes connecting the adjacent risers of the two sections together at the top and bottom, the pipe-piles at the ends of the battery formed by the risers, end pipes and connecting the top and bottom pipes being each in the form of a rhomboidal prism, the riser-couplings of one set of sections being staggered to the riser-couplings of the other set of sections.

41. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second battery-section of similar construction the component sections of which formed of the riser-couplings end and cross pipes have their cross-pipes alternately arranged between the cross-pipes of the first-named section, and pipes connecting the adjacent risers of the two sections together at the top and bottom, the pipe-pile at the end of the battery formed by the risers end pipes and connecting top and bottom pipes being each in the form of rhomboidal prism, the riser-couplings of one set of sections being staggered to the riser-couplings of the other set of sections.

42. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, a second battery-section of similar construction the component sections of which formed of the riser-couplings end and cross pipes have their cross-pipes alternately arranged between the cross-pipes of the first-named section, and pipes connecting the adjacent risers of the two sections together at top and bottom, the pipe-piles at the end of the battery formed by the risers, end pipes and connecting top and bottom pipes being each in the form of a rhomboidal prism, the riser-couplings of one set of sections being staggered to the riser-couplings of the other set of sections.

43. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second battery-section of similar construction the component sections of which formed of the riser-couplings end and cross pipes have their cross-pipes alternately arranged between the cross-pipes of the first-named section, pipes

connecting the adjacent risers of the two sections together at the top and bottom, and a return circulating pipe or pipes forming a communication between the top and bottom portions of the boiler, the riser-couplings of one set of sections being staggered to the riser-couplings of the other set of sections.

44. A water-tube boiler comprising a battery composed of a plurality of riser-pipes each formed of a plurality of **T**-couplings superposed one upon the other, the couplings in the same plane being connected in pairs to one another by end pipes which end pipes are connected together by curved cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a return circulating pipe or pipes forming a communication between the top and bottom portions of the boiler, the riser-couplings of one set of sections being staggered to the riser-couplings of the other set of sections.

45. A water-tube boiler comprising a battery composed of a plurality of riser-pipes each formed of a plurality of **T**-couplings superposed one upon the other, the couplings in the same plane being connected in pairs to one another by end pipes which end pipes are connected together by **S**-shaped cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, and a return circulating pipe or pipes forming a communication between the top and bottom portions of the boiler, the riser-couplings of one set of sections being staggered to the riser-couplings of the other set of sections.

46. A water-tube boiler comprising a battery composed of a plurality of riser-pipes each formed of a plurality of **T**-couplings superposed one upon the other, the couplings in the same plane being connected in pairs to one another by end pipes which end pipes are connected together by cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a steam drum or dome in communication with the risers at the top, and a return circulating pipe or pipes forming a communication between the top and bottom portions

of the boiler, the riser-couplings of one set of sections being staggered to the riser-couplings of the other set of sections.

47. A water-tube boiler comprising a battery composed of a plurality of riser-pipes each formed of a plurality of T-couplings superposed one upon the other, the couplings in the same plane being connected in pairs to one another by end pipes which end pipes are connected together by curved cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a steam drum or dome in communication with the risers at the top, and a return circulating pipe or pipes forming a communication between the top and bottom portions of the boiler, the riser-couplings of one set of sections being staggered to the riser-couplings of the other set of sections.

25 48. A water-tube boiler comprising a battery composed of a plurality of riser-pipes each formed of a plurality of T-couplings superposed one upon the other, the couplings in the same plane being connected in pairs to one another by end pipes which end pipes are connected together by cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a fire-box having the side and bridge walls in the form of a water-chamber in communication with the battery, and a return circulating pipe or pipes forming a communication between the top and bottom portions of the boiler, the riser-couplings of one set of sections being staggered to the riser-couplings of the other set of sections.

49. A water-tube boiler comprising a battery composed of a plurality of riser-pipes each formed of a plurality of T-couplings superposed one upon the other, the couplings in the same plane being connected in pairs to one another by end pipes which end pipes are connected together by curved cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a fire-box having the side and bridge walls in the form of a water-chamber in communication with the battery, and a return circulating pipe or pipes forming a communication between the top and bottom portions

of the boiler, the riser-couplings of one set of sections being staggered to the riser-couplings of the other sections.

50. A water-tube boiler comprising a battery composed of a plurality of riser-pipes each formed of a plurality of T-couplings superposed one upon the other, the couplings in the same plane being connected in pairs to one another by end pipes, which end pipes are connected together by S-shaped cross-pipes, a second battery-section of similar construction the component sections of which formed of the riser-couplings end and cross pipes have their cross-pipes alternately arranged between the cross-pipes of the first-named section, pipes connecting the adjacent risers of the two sections together at the top and bottom, a fire-box having the side and bridge walls in the form of a water-chamber in communication with the battery, and a return circulating pipe or pipes forming a communication between the top and bottom portions of the boiler, the riser-couplings of one set of sections being staggered to the riser-couplings of the other set of sections.

51. In a water-tube boiler the combination with a fire-box water-chamber and a steam-drum having ingress and egress openings in the bottom thereof and passages from said ingress-openings communicating with the extreme upper passages between tubes in the water-tube battery, of a plurality of return-tubes leading from the said egress-opening in the bottom of the steam-drum and extending beyond and without the heat zone of said fire-box and emptying adjacent to the bottom of said fire-box water-chamber through a lower circulating-pipe, substantially as described.

52. In a device of the class described, in combination, a water-tube battery of a plurality of sections, having one section formed of T-couplings, superimposed one on the other and connected in pairs by end pipes, and cross-pipes connecting said end pipes, and a section similarly arranged having its cross-pipes alternate with the cross-pipes of the first section, and pipes connecting the adjacent risers respectively of the two sections at the top and bottom thereof, a steam-drum surmounting said water-tube battery having ingress and egress openings in the bottom thereof, a plurality of pipes secured to and communicating with the uppermost portion of said battery and leading to said ingress-openings and lending support to said drum, a fire-box having a hollow wall forming a water-chamber, and return-tubes leading from said egress-opening in the steam-drum and extending beyond and without the heat zone of the fire-box and emptying to the bottom of the said fire-box water-chamber, substantially as described.

53. In a water-tube boiler, the combination with a hot-air chamber entirely inclosing

the battery of water and steam tubes, of a fire-box the sides and bridge walls of which form a continuous connected water-chamber which is in communication with the riser-pipes of the battery and is connected by a perpendicular return-pipe with the bottom of the steam-drum.

54. In a water-tube boiler, the combination with a hot-air chamber entirely inclosing the battery of water and steam tubes, of a fire-box the side and bridge walls of which form a continuous connected water-chamber which is in communication with the riser-pipes of the battery and is connected by a perpendicular return-pipe located outside of the battery-casing forming the heating-chamber with the bottom of the steam-drum.

55. In a water-tube boiler, the combination with a plurality of riser-pipes, of a plurality of curved substantially S-shaped horizontal circulating-pipes forming communication between the riser-pipes, the curves of the pipes being horizontal and all in the same plane and the ends of such S-shaped pipes extending beyond the loops of the S, and communicating with straight pipes.

56. In a water-tube boiler, the combination with a plurality of riser-pipes, of a plu-

rality of curved substantially S-shaped horizontal circulating-pipes forming communications between the riser-pipes, and a casing inclosing the battery so formed in such manner as to constitute a heating-chamber, the curves of the pipes being horizontal and all in the same plane and the ends of such S-shaped pipes extending beyond the loops of the S, and communicating with straight pipes.

57. In a water-tube boiler, the combination with a plurality of riser-pipes, of a plurality of curved horizontal circulating-pipes superposed in series one upon the other and in free communication at one end with the riser or risers on one side of the battery so formed, and at the other end with the riser or risers on the opposite side.

58. A circulating-tube for water-tube boilers of the shape of a cross elongated S the ends of which extend outward beyond the loops of the S, and all the curves of which are in the same plane.

59. In testimony whereof I have affixed my signature in the presence of two witnesses.

ALFRED JOHN RAYNOR.
